UNITED STATES PATENT OFFICE.

ARTHUR HAMMER, OF BERLIN, GERMANY.

IRONING-MACHINE.

1,032,402.

Specification of Letters Patent. Patented July 16, 1912.

Application filed June 1, 1911. Serial No. 630,562.

To all whom it may concern:

Be it known that I, ARTHUR HAMMER, a subject of the German Emperor, residing at Berlin, Germany, have invented new and useful Improvements in Ironing-Machines, of which the following is a specification.

This invention relates to ironing machines of the type in which a smoothing iron works in a rigid arm projecting from the machine frame, which iron works on the garment attached to an ironing table extending outward on all sides over the foot plate of the machine and capable of a suitable displacement.

The object of the present invention is to provide a single machine capable of completely ironing the whole shirt including the front.

The invention consists in an improved ironing machine of the type referred to in which the ironing table during the ironing may be pressed against or held away from, as desired, the iron which reciprocates in a fixed plane thereby enabling the front of the shirt to be subjected to an ironing operation in one direction only.

One example of the improved ironing machine according to the invention is illustrated in the accompanying drawings in which—

Figure 1 is a side elevation, Fig. 2 a front elevation, Fig. 3 a plan of an ironing table used in combination with the ironing machine for ironing the shirt front, Fig. 4 is a sectional view of a detail of this ironing table, Figs. 5 and 6 illustrate in plan and side elevation respectively and to a larger scale a device for stretching the neck-band, used in combination with the ironing table of Fig. 3. Fig. 7 represents a sleeve blank. Fig. 8 represents a cuff ironing board.

The machine consists substantially in a frame or standard *a* supporting laterally the driving mechanism, from which standard there projects at the front an arm *c* carrying the smoothing iron *b*; the base of the standard supports the column *d* for the ironing table *e*, along with the mechanism for the elevation and drawing forward of the table. The smoothing iron *b* to which steam for heating is supplied by means not shown in the drawing is mounted at the lower end of the arm *c* in suitable guides enabling it to move in a horizontal plane. This movement is one of reciprocation and is effected by means of a crank disk *f*, the

shaft of which is driven from the belt pulley *h* through a coupling or clutch which can be engaged or disengaged by the hand lever *g*. The crank pin is connected by a rod *i* with a pin on the rear side of the smoothing iron.

The ironing table *e* is guided by means of a downward projecting sleeve in vertical direction on its column *d*, and in a horizontal direction at right angles to the motion of the smoothing iron by means of dovetail guides. The up and down motion of the table is effected by means of a toggle *k* one end of which is pivoted to the bottom of the machine frame and the other to the sleeve guide of the table. The middle fulcrum of the toggle is connected through a link *l* with one end of a bell crank lever the other limb of which is formed as a pedal *m* for the operator of the machine. The joint connecting the pedal lever to the link is provided with flutings in order to present a secure grip for the foot of the operator.

The outward motion of the ironing table *e* is effected by means of a hand lever *n'* pivoted at *n* and provided with an upwardly directed arm *o* provided with a pin *o'* which engages in a vertical slot guide *s'* in the table, a counterweight being arranged on the said lever in such a manner that the table is normally held in position underneath the smoothing iron.

The smoothing iron has a semicircular recess on its right side corresponding to the neck-band of the shirt. On the left side the ironing table overhangs its column for a considerable distance so that the smoothing iron in its middle position lies nearly over the center of the shirt front.

According as the back, sides, cuffs, neck-band, or front of the shirt are to be ironed several boards are used as backing the sizes of which decrease regularly so that they can be laid one over another on the ironing table without interfering with the work. Along with the cuff ironing board *b'* serving as backing when ironing the sleeves, a so-called sleeve blank *a'* is used, consisting of a thin board having the form of a flat folded sleeve, over which sleeve blank the sleeve is drawn to enable it to be ironed.

The board or table for the ironing of the front of the shirt is illustrated in Figs. 3 and 4. It consists of a rectangular board or preferably of a plate of aluminium, provided with the device illustrated in Figs. 5 and 6 for stretching the neck-band, this de-

vice being arranged at the place denoted by the circle in Fig. 3. At the opposite end the board is provided with a roller p which serves the purpose of stretching out the shirt which is held fast at the neck-band and shoulders. For this purpose the lower end of the shirt is wrapped about the roller p and the latter is turned until the desired tension is attained. The roller is maintained in this tensioned position by means of a pawl seen at the left-hand corner of the board. The roller p lies somewhat below the plane of the board surface so as not to be in the way of the reciprocating smoothing iron.

The clamps q for securing the shirt at the shoulders consists of two plates r and s the first of which is mounted firmly and the other loosely on a screw bolt t . These screw bolts are also provided at their heads with a clamp arm u which coöperates with a wedge segment attached to the upper plate s in such a manner that by moving the clamp arm to one side the plate s , which is preferably provided at its front edge with downwardly pointing teeth, the plate is pressed upon the clasped shoulder of the shirt.

The device for stretching the neck-band consists of two semicircular wooden disks v and v' . The two disk halves are mutually guided by means of pins w in the disk v which slide in corresponding holes in the other half v' . In two lugs attached to the half v is journaled a transverse spindle x provided with an arm y and carrying a lever z at each end, to which levers is jointed a metal strap 2 embracing the periphery of the disk half v . On the disk half v' is pivoted a cam disk 3 the edge of which is in contact with the straight edge of the part v . On rotation of this cam disk the parts v and v' are moved away from each other. This stretching device works in the following manner. The neck-band previously ironed in spread out position is placed with the open side underneath the strap 2 and the latter pressed down by depressing the arm y by means of a clamp arm 4 . The disk halves v and v' are then caused to move away from each other by rotation of the cam disk 3 until the necessary tension is attained. The neck-band being thus stretched the shoulders are secured by means of the clamps q and the shirt tensioned over the board by tightening up the roller p in the manner already described. In this condition the board is placed on the ironing table which for this purpose is drawn forward from under the smoothing iron by means of the lever n' . After the ironing table has been pushed back underneath the smoothing iron the ironing may begin. This is effected by first elevating the table by leaning with the weight of the

body on the pedal m and then starting the smoothing iron by operating its coupling. On its motion to the right the semicircular recess in the iron encounters the stretching device for the neck-band and thereby pushes the ironing board to the outer end of its stroke, where it remains. During the actual ironing a pressure will obviously be exerted on the ironing table by means of the pedal lever while the motion of the iron is to the left and on the reverse motion the pressure will be removed so that the iron moves freely over the shirt on the table. By this means the shirt front which can be firmly tensioned from the neck-band side, will be subjected only to pull during the actual ironing and the forming of folds will thus be prevented. The alternate lifting and lowering of the ironing table which must be synchronous with the reciprocation of the iron produced by the driving crank disk, is easily effected by the operator who stands on the pedal plate m with one foot on the joint connecting the pedal lever with the link l and leans the weight of his body alternately on one foot or the other in time with the reciprocation of the iron, supporting himself by means of a hand grip on the front of the arm c . The operator by these means has complete control of the up and down motion of the ironing table and also of the degree of pressure on the ironing table while at the same time he can easily follow the reciprocation of the iron. When the actual ironing is finished the ironing table preferably by pressure and with the machine at rest, is held for a certain time against the iron in order to completely dry the shirt. The remaining parts of the shirt are proceeded with in similar manner using corresponding boards and blanks, but in this instance the ironing may take place at both strokes of the iron. It may be stated that by using the herein-before described stretching device for the neck-band, shirts with fixed collars may be completely ironed.

What I claim is:

1. In an ironing machine a vertically movable ironing table extending outward on all sides over the foot plate of the machine frame, a rigid arm projecting from the machine frame above said ironing table, an iron capable of being reciprocated in guide-ways of said arm, means for moving up and down said ironing table, said means consisting of a toggle and a bell crank lever upon which the operator stands, one arm of said toggle being connected with said ironing table, the other one being connected with the foot plate of the machine, the central fulcrum of said toggle being connected by a link with one arm of said bell crank lever, a foot grip positioned at the connection of said link with said arm, the other

arm of said bell crank lever being formed as a pedal, and means for actuating said iron.

2. In an ironing machine a vertically 5 and horizontally movable ironing table extending outward on all sides over the foot plate of the machine frame, a rigid arm projecting from the machine frame above said ironing table, an iron capable of being 10 reciprocated in guide-ways of said arm, means for moving up and down said ironing table, said means consisting of a toggle and a bell crank lever upon which the operator stands, one arm of said toggle being 15 connected with said ironing table, the other one being connected with the foot plate of the machine, the central fulcrum of said toggle being connected by a link with one

arm of said bell crank lever, a foot grip positioned at the connection of said link with 20 said arm, the other arm of said bell crank lever being formed as a pedal, a hand lever connected with the machine frame, said hand lever having one arm engaging in a slot guide of said ironing table and being 25 provided with a counter weight normally holding said table in position underneath said iron and means for actuating said iron.

In testimony whereof I have signed my 30 name to this specification in the presence of two subscribing witnesses.

ARTHUR HAMMER.
